UNITED STATES PATENT OFFICE.

WILLIAM J. HAMMOND, OF CHICAGO, ILLINOIS.

ANTISHIFTING MEANS FOR PILED METAL SHEETS.

Application filed May 20, 1925. Serial No. 31,552.

To all whom it may concern:

Be it known that I, WILLIAM J. HAMMOND, a citizen of the United States, residing at Chicago, in the county of Cook and State of Illinois, have invented new and useful Improvements in Antishifting Means for Piled Metal Sheets, of which the following is a specification.

The primary object of my invention is to provide comparatively simple and inexpensive means of superior effectiveness in preventing metal sheets, and the like, in piles thereof undergoing transportation, from shifting and consequent damage.

I have more particularly devised my invention for an improvement on the practice of shipping metal sheets in box-cars wherein it is usual to stack them in piles, though my improved means may be similarly used in other transporting vehicles, including boats and trucks having floors, and for securing in place therein, as well as in box-cars, other merchandise. However, having devised my anti-shifting device particularly for use in box-cars, it is hereinafter described in that connection.

It is common practice, in shipping metal sheets in box-cars, as from sheet-steel manufacturing plants, to pile the sheets in opposite sides of opposite ends of the car to leave the doorways unobstructed, and to provide a longitudinal aisle between the piles to facilitate handling of the sheets.

The loading rules of the American Railway Association are very exacting with regard to bracing the piles to prevent damage in transit, as by shifting thereof and of the sheets therein in yard-switching of the cars and by the jolting to which they are subjected in motion.

To observe these loading rules it is quite general practice to support each pile on stationary wedge-blocks at its opposite ends, to provide wooden uprights at those ends secured by cleats nailed to the car-floor and to extend wooden bracing means between pairs of the piles, all this requiring much lumber, which becomes largely wasted because having, anyway for the most part, only a single use, and involving the work of skilled labor for several hours of installation by a competent carpenter, with attendant expense. And nevertheless, it is not an infrequent occurrence for such elaborate

bracing to be ineffective in its purpose, the piles sometimes shifting bodily with resultant damage to the car-ends, or becoming disorganized and permitting sheets to shift on or even off them, with resultant damage, particularly in the way of bending their edges, and especially their corner-portions, thereby rendering them unfit for intended uses and requiring their return to the mill for re-rolling, with consequent loss to the shipper and dissatisfaction to the customer.

The aforesaid and other objections are overcome by my improvement illustrated in the accompanying drawing, in which—

Figure 1 is a broken sectional plan view of a portion of a box-car loaded in accordance with my improvement;

Fig. 2 is a broken view showing a section on line 2—2, of Fig. 1;

Fig. 3 is a similar view showing a section on line 3—3, Fig. 1;

Fig. 4 is a similar view showing a section on line 4—4, Fig. 2, and

Fig. 5 is a section on line 5—5, Fig. 1, of one of the upper of the two bars between which the sheets in a pile thereof are confined against shifting.

The box-car A represented embodies no features of novelty, but may involve any ordinary or suitable construction. Metal sheets to be transported in the car are customarily disposed in one or more stacks B, each stack occupying an end-portion of a side of the car to leave the doorways C unobstructed and afford between the inner sides of opposite stacks an aisle D to facilitate piling the sheets and their removal from each pile. In Fig. 1, a pile B of the metal sheets is shown in one side of the car equipped with my complete anti-shifting means, whereas the opposite pile is merely represented in outline by dotted lines without the top members of said means being placed for exerting the tightening function hereinafter described. It is desirable and customary to prepare for piling the sheets by securing to the car-floor similar wooden bracing blocks 6 of wedge-shape, for supporting the pile at its opposite ends, a set of two such blocks being shown at each end, in Fig. 1; and cleats 6^a are shown nailed to the floor to reinforce the blocks. The pile being thus supported sags, as represented in Fig. 2, between the pairs of wedge-blocks,

and may contact therebetween with the car-floor, on which it is furthermore customary and desirable to fasten wooden cleats 7 at opposite sides of the pile to stay it laterally.

5 The bracing means thus described as being hitherto used may be desirably, but not necessarily employed with my improvement, described as follows:

- 10 Adjacent each end of a pile of the sheets to be stacked, and near the inner ends of the respective blocks 6, is laid, to extend across the pile B in frictional contact with the car-floor, a bottom-bar 8, preferably of metal and of greater length than the width 15 of the pile to be formed, in order that it shall project beyond the sides thereof, where it is provided with holes 8^a for the rods hereinafter described. For the bars 8, I prefer to use those of channel-form because 20 under the weight upon them their flanges will engage the car-floor in a manner tending to prevent slipping; and also because of the strength of that form of bar. And, since the metal bar should not contact with 25 the lowermost sheet, because of liability of marring it, I provide a cushioning medium, which should be of the length and width of the metal bar and contain holes to register with the holes 8^a, a bar 8^b of soft-wood, 30 such as pine, being most desirable for the purpose of thus supplementing the bar 8; and the two affording practically a single cushioning bar. Moreover, the tops of the cushioning bars should slant, as shown in 35 Fig. 2, to conform to the inclination of the portion of the pile B bearing thereon, thereby to avoid tilting of the bottom bars on their inner flanges under the weight of the pile 8 and cause substantially uniform bearing of the two bar-flanges throughout their 40 length.

- With a pile or piles B loaded into the car, bars 10, preferably like the bars 8 in form and dimensions and provided with holes 45 like the holes 8^a to register with the latter, and also provided with cushioning means 10^a, are laid across the top of the pile near its opposite ends, but with each preferably slightly offset from the relative bottom bar, 50 as represented in Fig. 2, for the purpose hereinafter explained. The cushioning means in this instance is also preferably a bar of soft wood, and it is shown fitting within the hollow of the channel-bar, the 55 flanges of which meet shoulders (Fig. 5) behind an expanded face of the wood to bear against the uppermost sheet of the pile and avoid the undesirable metal-against-metal marring contact, hereinbefore referred to. 60 The open side of the channel-bar 10 on top of the pile B being undermost, enables the cushioning medium 10^a to form a permanent part of the bar, and may be fastened in place, as by screws 11. 65 With the bottom-bars 8 and top-bars 10

in place, metal rods 12, which may be solid or tubular, are applied by passing a rod through their respective holes at each side of the pile and forcing the bars 10 against the top of the pile to tighten the metal sheets in place. Each rod is provided on its lower end with a stop, shown as a nut 13, and is threaded along its upper portion for working a nut 14 thereon, as the preferred means for cooperating with the rods to force 70 down the top-bars for tightening the metal sheets in the pile against shifting.

The purpose, in applying the top clamping bar in offset relation to its companion bottom bar, is to cause each rod to extend 80 through a perpendicular plane at right angles to the tangent to the surface of the pile at that point, and thus produce flatwise bearing against the uppermost sheet of the bar 10 in tightening the nuts 14 to confine 85 the sheets in the pile.

It will thus be seen that the several sheets are held tightly together in superposed relation and prevented from displacement, and that the weight of the pile of sheets causes 90 the lower bar to frictionally engage the transporting vehicle thus preventing the shifting of the pile of sheets as a whole.

A box-car loaded with four piles of metal sheets may be completely equipped with my 95 improved anti-shifting means by an unskilled laborer in thirty minutes, as against several hours a carpenter requires for cutting and placing the lumber (mostly two-by-fours) for the pile-bracing purpose as 100 hitherto practised.

I realize that considerable variation is possible in the details of construction of my invention thus shown and described, and I do not intend to be limited thereto except 105 as pointed out in the appended claims, in which it is my intention to claim all the novelty inherent in my invention as broadly as permissible by the state of the art.

I claim—

1. Anti-shifting means for piled metal sheets whereby to prevent their displacement, either singly or as a mass, while in transit, comprising a lower pile-supporting bar of a length to cause its ends to project beyond the sides of the pile said bar frictionally engaging the transporting vehicle in degree proportionate to the weight of the sheets piled thereon, an upper bar extending across the top of the pile with its ends projecting beyond the sides thereof, means connecting the ends of said bars, and tightening means co-operating with said bars-connecting means to confine the piled sheets between said bars. 110

2. Anti-shifting means for piled metal sheets in transit, comprising a lower channel-bar extending across the bottom of the pile and a bar extending across the top thereof, each bar being of length to project 115 120 125 130

- beyond the opposite sides of the pile, rods connecting said bars at their end-portions, and tightening means cooperating with the rods to confine the piled sheets between said bars.
3. Anti-shifting means for piled metal sheets in transit, comprising a pair of channel-bars of greater length than the width of the pile to extend the members in parallel relation respectively across the bottom and top thereof and project them beyond its sides, rods connecting said bars through their end-portions and having threaded upper ends, and nuts on the threaded rod-ends for releasably confining the piled sheets between said bars.
4. In combination with a pile of metal sheets, or the like, stacked for transit in a car, anti-shifting means comprising a cushioning channel-bar of greater length than the width of the pile extending across the bottom thereof, a channel-bar similarly extending across the top of the pile and containing a bar of cushioning material bearing against the pile, rods connecting said bars at their end-portions, and tightening means cooperating with the rods to confine the piled sheets between said bars.
5. In combination with a pile of metal sheets, or the like, stacked for transit in a car, bars extending respectively across the bottom and top of the pile near each end thereof and beyond its sides with the lower bar bearing on the car floor, rods connecting each lower bar at its projecting ends with those of the corresponding upper bar, and tightening means cooperating with the rods to releasably confine the piled sheets between said upper and lower bars.
6. In a car having metal sheets, or the like, stacked in piles in opposite sides of the car to form an intermediate aisle, with each pile resting at its opposite ends on wedge-blocks secured in place, anti-shifting means for the stacked metal sheets, applied between the inner ends of the opposite pairs of wedge-blocks and comprising for each end-portion of a pile a pair of bars having its members extending respectively across its bottom and top and beyond the sides thereof, end-threaded rods connecting the members of each pair of the bars at their projecting end-portions, and nuts on the threaded rod-ends for releasably confining the sheets between said bars.
7. In a car having piles of metal sheets, or the like, stacked in opposite sides thereof to form an intermediate aisle, with each pile resting at its opposite ends on wedge-blocks secured in place, anti-shifting means for the stacked metal sheets, applied between the inner ends of the opposite pairs of wedge-blocks and comprising for each end-portion of a pile a pair of cushioning channel-bars having its members extending respectively across the bottom and top and beyond the sides thereof, rods extending through and connecting the members of each pair of the bars at their projecting end-portions and having their upper ends threaded, and nuts on the threaded rod-ends for releasably confining the sheets between said bars.

WILLIAM J. HAMMOND.
